UNITED STATES PATENT OFFICE.

ORLANDO S. GAUCH, OF SHELBY, OHIO, ASSIGNOR TO THE SHELBY PRINTING COMPANY, OF SHELBY, OHIO, A CORPORATION OF OHIO.

CARBON-HOLDER.

1,054,761.

Specification of Letters Patent.

Patented Mar. 4, 1913.

Application filed August 19, 1911. Serial No. 645,042.

To all whom it may concern:

Be it known that I, ORLANDO S. GAUCH, a citizen of the United States of America, residing at Shelby, in the county of Rich-
5 land and State of Ohio, have invented cer-
tain new and useful Improvements in Car-
bon-Holders, of which the following is a
specification.

My invention relates to carbon holders
10 and is especially adapted to be used in con-
nection with manifold order or sales books.

The objects of my invention are to provide
15 a carbon holder that will secure the carbon
sheet rigidly in place with relation to the
sales or order book; to prevent sagging of
the holder and the tendency of either part
20 to spring away from each other; to provide
a carbon holder that can be attached to the
ordinary spring clip that is used for hold-
ing the pad securely to the cover. These
and other objects are attained by the mech-
anism illustrated in the accompanying draw-
ings in which:—

Figure 1 is a perspective view of a sales
25 or order book embodying my invention,
showing the usual cover and spring clips
applied thereto. Fig. 2 is a side view in
perspective, of my carbon holder, showing
the parts open preparatory to inserting the
30 carbon sheet between the clamping parts.
Fig. 3 is a cross sectional end view, showing
both of the parts closed with the carbon
sheet interposed between them.

In the drawings reference numeral 1 repre-
35 sents a cover, 2 an order or sales book
mounted upon the cover, and 3 and 4 spring
clips which yieldingly press down upon the
order or sales book, thereby keeping the
leaves of the manifold order or sales book
40 from becoming disarranged in any manner.

The carbon holder comprises a part of
the spring clip 4 which will be described
hereinafter. The spring clips are fastened
45 to the cover in any well-known manner, it
being necessary only to attach them so as
to provide for downward pressure or ten-
sion against the order or sales book.

The above described elements do not form
any part of my invention.

50 I will now describe my carbon holder,
which is applied to and used in combination
with the above described elements.

Reference numeral 5 designates a channel
bar, having a portion of the upstanding
55 flanges adjacent to and at its extremities

cut away to the bottom 6, leaving flat por-
tions 7 and 8. Slots 9 and 9 are provided
in the flat portion 7 and 8 and the margin
on each side of the slot is turned to form
eyes 10, 11, 12 and 13. A clamping bar 14
60 having rounding side portions 15 and 16
is provided to fit the flanges 17 and 18 of
the channel bar and is hinged upon the free
end 19 of the spring clip 4, between the eyes
12 and 13 of the channel bar. One end of
65 the channel bar is also carried by the free
end 19 of the clip 4. The opposite end of
the channel bar is carried by the free end 21
of the clip 4. One end of the clamping
bar 14, is provided with a hook 20. Pro-
jections 22—22—22 are pressed from and ex-
70 tend up from the bottom 6 of the channel
bar. A groove or recess 23 is formed upon
the under surface of the clamping bar, alin-
ing with the projections 22—22—22.

75 The carbon sheet is represented by the let-
ter A.

In the operation of my carbon holder the
carbon sheet A is interposed between the
channel bar 5 and clamping bar 14, as
80 shown clearly in Fig. 3. The clamping bar
is then pressed downward and the hook 20,
on its inner side, engages with the periphery
of the free end 21 of the spring clip 4, there-
by yieldingly holding the channel and 85
clamping bar in close contact with the car-
bon sheet interposed between them. The
projections 22—22—22 press the portion of
the carbon sheet, lying over it, into the re-
cess or groove 23, and at the same time the 90
rounding edges 15 and 16 of the clamping
bar 14 press the carbon sheet against the
flanges 17 and 18, securely holding the car-
bon sheet in place and preventing the tear-
ing of or disarrangement of same. 95

What I claim is:—

1. A carbon sheet holder for books and
the like comprising a channel-bar, a clamp-
ing bar having upturned sides hinged to said
channel bar and adapted to fit within the 100
flanges of the channel bar to securely retain
a carbon sheet between them, and means to
connect the channel bar to the back of the
book.

2. A carbon sheet holder for books and the 105
like comprising a channel bar having a se-
ries of projections raised from the bottom,
a clamping bar hinged to said channel bar
and provided with a longitudinal groove
that alines with said series of projections, 110

and means to connect the channel bar to the back of the book, substantially as and for the purpose described.

3. A carbon sheet holder for books and the like comprising a channel bar, a clamping bar hinged to said channel bar and adapted to fit within the flanges thereof, and means to yieldingly connect said channel bar to the back of the book, as and for the purpose described.

4. A carbon sheet holder for manifold order or sales books comprising a channel bar with flat end portions, eyes formed on said flat portions, a yielding member connected to the back of the book and fitted to said eyes, a clamping bar hinged to said channel bar and provided with means on its

free end to engage said yielding member, substantially as and for the purpose described.

5. A carbon sheet holder for books and the like comprising a channel bar provided with eyes on its extremities, a yielding member carried by the book back and connected to said eyes, a clamping bar hinged to said channel bar to engage therewith and provided with means to securely lock the bars together, as and for the purpose described.

In testimony whereof I affix my signature in presence of two witnesses.

ORLANDO S. GAUCH.
